DOORLOCK

Etienne Arthur Renevey, Thonex, Switzerland

Application April 24, 1933, Serial No. 667,759
In France May 2, 1932

12 Claims. (Cl. 70—29)

This invention relates to door locks and its principal object is the provision of a lock having a bolt which may be secured in locked position by means actuated by an operating member, as 5 for instance the door knob, from the outside of the space closed by the door, without requiring a key for such locking operation, a key or combination being however necessary to unlock the door from the outside after it has thus been 10 locked.

The accompanying drawings show two embodiments of a lock according to the invention.

Figure 1 is a vertical section through a lock according to the invention.

15 Figures 2 to 5 show the operation of this lock in diagrammatic manner.

Figure 6 is a vertical section of a further form of a lock according to the invention.

Figures 7 and 8 are transverse sections through 20 a part of the lock in two different working positions.

Figure 9 is a transverse section through the key tube of a lock according to the invention.

Figure 10 shows a master key which may be 25 used with some of the represented locks.

Figure 11 shows a modified detail of the lock according to Fig. 6.

Figure 12 shows a master key which may be used with the modification represented in Fig. 30 11.

The lock construction according to Figures 1 to 5 comprises also a lock bolt 1 and a latch bolt 2. The door knob 23 is mounted for rotation with the arm 24 adapted to act on the pin 9 of the latch, and with the arm 25 acting on the pin 8 of the bolt. On the square 4 of the knob is also mounted a lever 35.

The locking device for the bolt 1 comprises a series of tumblers 26 rotatably mounted on a pin 27 carried by the lock frame. The tumblers are subjected to the action of a spring 22 and are provided with an opening 28. The openings 28 of all the tumblers are exactly in line with each other and the upper edge of the opening is provided with two projections 30 and 31 cooperating with a finger 32 carried by the bolt. The lower edge of each tumbler is provided with a projection 34 and with a recessed portion 29, this recessed portion having a different contour 33 for each tumbler to be capable for cooperation with a key.

Figs. 2 to 5 show the operation of the lock bolt in diagrammatic manner. When the bolt is in retracted position (Fig. 2), its finger 32 is engaged behind the projections 31 of the different

tumblers. In order to lock the bolt, the door knob 23 will be turned upwards; the lever 35 then passes beneath the projections 34 and raises the tumblers about their pivot 27 so that the projections 31 release the finger 32, and when further turning the knob in upward direction the arm 25 pushes the bolt into locking position (Fig. 4), then the knob is released and owing to its weight or to spring action it returns into its normal horizontal position, the lever 35 and arm 10 25 moving backwards with the knob.

The lever 35 releases the projection 34 and the tumblers turn downwardly about their pivot so that the projections 30 engage behind the finger 32 (Fig. 5) and maintain the bolt in locked position. In order to open the bolt a key will be introduced into the opening 36, the contour of the key having a shape corresponding to the edge portion 33 of the tumblers, so that when turning the key, the tumblers will be raised and the projections 30 release the finger 32. At the same same time the key enters into a notch 37 provided in the bolt and rotation of the key retracts the bolt so that the finger 32 is placed between the projections 30 and 31 of the tumblers. 25 A second turn of the key raises again the tumblers and the key enters into a second notch 38 in the bolt and completely retracts this latter.

When the bolt is in closed position it is preferred that the knob 23 and the lever 35 cannot be 30 raised and act on the tumblers, since it would then be possible to introduce a wire through the key opening into the notch 37 and retract the bolt while the tumblers are raised. In order to prevent this, the bolt carries a yieldable pawl 39 35 which, when the bolt is in locking position, abuts against the lever 35 when it is tried to turn the knob and prevents any rotation of the knob and the lever.

The form of lock shown in Figs. 6, 7 and 8 is 40 particularly applicable to automobile doors. A latch bolt 50 is urged into closing position by a spring 51. The door knob 52 is normally in horizontal position and is mounted on a square shaft 4 carrying also a cam member 53 which controls 45 two intermediary members 54 and 55. The member 54 is provided with a slot 56 engaging a pin 57 carried by the cam. When the knob 52 is downwardly turned, the cam 53 turns with the knob and the pin 57 acts on the member 54 50 which turns also and bears on the pin 58 carried by the bolt to retract the bolt for opening the door. When the knob is released, the spring 51 brings the cam 53 and the intermediary lever 54 back to normal position and closes also the latch 55.

bolt. The second intermediary member or locking member 55 can move vertically. It is provided with a projection 59 engageable into a notch 60 of the bolt 50. The portion 61 of the intermediary member is normally resting on the cam member 53 in its lowered position as shown in dot and dash lines in Fig. 6.

When the knob 52 is turned upwardly, the portion 62 of the cam acts on the member 55 and moves this member upwardly so that the projection 59 is introduced into the notch 60, while the nose 61a is moved into engagement with the pin 59a carried by the member 54. The intermediary member 55 is maintained in this raised position by a locking device which will now be described.

This locking device comprises four tumbler levers mounted on an axis 63 and subjected to the action of spring 63a. One of the tumblers 64 is provided with a projection 65 and an inclined edge 66. The three other levers 67 have no projection 65 and in the place of an inclined edge 66 they are provided with corners 68. The intermediary member 55 carries at its lower end a sleeve 69 into which penetrate the four tumblers 65 and 67 when the bolt is unlocked (Fig. 7). When the intermediary member is raised upon turning the knob and locks the bolt, the sleeve 69 moves into the position shown in Fig. 8 and the springs 63a push the four tumblers beneath the edge of the sleeve, so that the intermediary member 55 is locked against downward movement and the bolt 50 against being retracted.

The intermediary member 55 carries also a pawl 75 which a spring 75a tends to maintain against a pin 75b. When the member 55 is in raised position, the pawl abuts against a projection 76 of the cam member 53. This latter and therefore also the knob 52 cannot be actuated when the bolt is locked.

In order to unlock the bolt, a key must be introduced into the tube 70 which corresponds to the shape of the tumblers in order to bring each tumbler in line with the opening of the sleeve 69 so that the intermediary member 55 will fall downwards and free the bolt as also the door knob 52. It is however possible to unlock the door without the aid of a key from inside of the automobile by exerting a pull on the button 16 connected to a rod ending in a hook 17 which engages the four tumblers 64 and 67, whereby these tumblers are brought out of engagement with the locking member 55 and this latter can fall down to release the member 54 and the latch bolt 50.

It will be remarked that when the tumblers lock the intermediary member 55 (Fig. 8) it would be possible by introducing a wire in the tube 70, to push the tumbler 64 into its releasing position which is obtained when the nose 65 abuts against the lock casing. But in order to unlock the bolt also the three tumblers 67 must be brought into releasing position and this is practically impossible by means of wires, because as the movement of rotation of these tumblers is very small, one or the other of them will always be pushed a little too far and will engage beneath the opposite wall of the sleeve 69 and prevent its release.

In locks for automobile doors the square shaft 4 carrying the handle 52 on the outside of the door, does sometimes not carry a handle on the inside of the door. The inside handle is often placed at some distance away from the lock 75 about in the center of the car door to permit con-

venient opening of the door from the inside of the car, and then the inside handle is directly coupled to the latch bolt by means of a pull rod retracting the latch bolt when the handle is operated. In this case the inside handle can naturally not be actuated to effect locking of the latch bolt by moving the locking member 55, and in order to permit such locking from the inside of the car, the locking member 55 carries a horizontally extending pin 89 penetrating through a slot 90 provided in the lock casing 91 to project from the inside of the door. The pin 89 can be seized by the fingers from the inside of the car to move the locking member 55 into locking position.

Figure 9 shows a section through a tube 70 in which such intermediary pieces are spaced from each other. Figure 10 shows a master key which may be used to open a series of locks having tumblers and intermediary pieces as shown in Fig. 9. This key is provided with a shoulder 72 and with four tongues 73 separated by slits 74. The shoulder 72 acts against one of the intermediary pieces, while the tongues 73 pass between these pieces and act directly on the tumblers to bring them into releasing position.

This key can thus open a series of locks of which three of the intermediary pieces 71 acting on the tumblers may be of various lengths, while the fourth piece will always have the same length to coact with the shoulder 72. There could be provided also two shoulders 72 at different heights of the key.

Instead of using a key which acts when a pushing force is exerted on it, it will also be possible to use a rotary key as is shown in Figs. 11 and 12. In Fig. 11 four tumblers 78 can turn on their axis 79. One end of the tumblers coacts with a sleeve 80 similar to the sleeve 69 in Figs. 6 to 8. The tumblers have different shaped contours 81 which cooperate with the stepped face 82 of a key 83. The Figure 12 shows a master key which may be used with this construction. This key is provided with a shoulder 85 cooperating with the edge 81 of the first tumbler, and with three grooves 86 passing over the edges of the three other tumblers without touching the edges 81. These three tumblers are then turned by the tongues 87 of the key acting on projections 88 provided on the faces of the tumblers.

It is to be understood that the invention is not limited to the details of construction as shown and described and which have been given by way of example only. It is possible, for example, to use a combination key instead of an ordinary key to unlock the bolts, or to use any other system of door knob for actuating the means which lock the bolt.

I claim:

1. A lock comprising a rotatable handle, a latch bolt, means mounted for rotation with the handle and operatively connected to the latch bolt for retraction of the bolt upon rotation of the handle in one direction from normal position of rest, a locking member operatively connected to said handle to be moved upon rotation of the handle in opposite direction from its normal position of rest, means on said locking member abutting against said latch bolt retracting means upon the locking member being moved by rotation of the handle for preventing movement of the handle in that direction in which it would retract the latch bolt, and locking means for holding said locking member in the position in which

it prevents movement of the handle to retract the latch bolt.

2. A lock comprising a latch bolt, an operating handle, means mounted for rotation with the handle for retraction of the latch bolt upon rotation of the handle in one direction from its normal position of rest, a slidable locking member, means mounted for rotation with the handle for moving said locking member into active position upon rotation of the handle in the other direction from its normal position of rest, said locking member upon being moved to active position engaging with said latch bolt retracting means to prevent rotation of the handle in the direction corresponding to retraction of the latch bolt, and tumbler means locking the bolt member in active position and coacting with a key for releasing the bolt.

3. A lock mechanism for vehicle doors comprising a latch bolt, a slidable locking member, a handle member rotatable in one direction from its normal position of rest for retraction of the latch bolt and rotatable in the other direction for moving the locking member into active position, means carried by the handle member and engaging with the locking member upon this latter being moved into active position for retaining the handle member in its normal position of rest, spring actuated tumbler means engaging said locking member in active position and cooperating with a key introduced from the outside of the space closed by the door for releasing the locking member, and a hook member engageable with the tumbler means for disengaging the locking member from the inside of the space closed by the door.

4. A lock mechanism for vehicle doors, comprising a latch bolt, a slidably mounted locking member, a handle member rotatable in one direction from normal position of rest for retraction of the latch bolt and rotatable in the other direction for moving said locking member into engagement with the latch bolt for preventing retraction of the latch bolt, tumbler means for maintaining the locking member in latch bolt engaging position, said tumbler means being operable by a key introduced from the outside of the space closed by the door for releasing the locking member, and a hook member operable from the inside of the space closed by the door for releasing the locking member.

5. A door lock comprising a latch bolt, a locking member for said latch bolt, a handle member rotatable in one direction for retraction of the latch bolt and rotatable in opposite direction for moving said locking member into engagement with the latch bolt, spring actuated tumbler means for retaining the locking member in latch bolt engaging position, means carried by the handle member and engaging with the locking member upon this latter engaging the latch bolt for preventing rotation of the handle member in the direction corresponding to retraction of the latch bolt, a pawl carried by the locking member, and means carried by the handle member and engaging with said pawl upon the locking member being in latch bolt engaging position for preventing rotation of the handle member also in the opposite direction.

6. A lock comprising a rotatable handle, a slidably locking member movable into locked and unlocked positions, means operatively connecting the locking member to the handle for moving the locking member from unlocked to locked position upon a movement of rotation of the handle in

one direction from normal position of rest, said means being inoperative when returning the handle to normal position of rest after having moved the locking member to locked position, a yieldable pawl carried by the locking member, and means mounted for rotation with the handle and adapted to engage with said pawl upon the locking member being in locked position to thereby prevent movement of the handle in said direction corresponding to movement of the locking member from unlocked to locked position.

7. A door lock comprising a latch bolt, an operating handle movable in opposite directions from its normal position of rest, means mounted for movement with the handle to retract the latch bolt upon movement of the handle in one direction from its normal position of rest, a locking member coacting with said latch bolt retracting means, means mounted for movement with the handle to move said locking member to locking position upon movement of the handle in the other direction from its normal position of rest, said locking member upon being moved to locking position engaging with said latch bolt retracting means to prevent movement of the handle in the direction corresponding to retraction of the latch bolt, and tumbler means engaging with said locking member as this member is moved to locking position and adapted to coact with a tumbler actuating member for releasing the locking member from locking position.

8. A door lock comprising a latch bolt, an operating handle movable in opposite directions from its normal position of rest, means mounted for movement with the handle to retract the latch bolt upon movement of the handle in one direction from normal position of rest, a locking member coacting with said latch bolt retracting means, means mounted for movement with the handle to move said locking member to locking position upon movement of the handle in opposite direction from normal position of rest, said locking member upon being moved to locking position engaging with said latch bolt retracting means to prevent movement of the handle in the direction corresponding to retraction of the latch bolt, and spring pressed tumbler means automatically engaging the locking member when said member is moved to locking position, said tumbler means being adapted to coact with a key for releasing the locking member.

9. A lock for vehicle doors comprising a latch bolt, an operating handle on the outside of the door and movable in opposite directions from normal position of rest, means mounted for rotation with the handle to retract the latch bolt upon movement of the handle in one direction from normal position of rest, a locking member coacting with said latch bolt retracting means, means mounted for rotation with the handle to move said locking member into locking position upon movement of the handle in opposite direction from normal position of rest, said locking member upon being moved to locking position engaging with said latch bolt retracting means to prevent movement of the handle in the direction corresponding to retraction of the latch bolt, tumbler means for holding the locking member in locking position and adapted to coact with a tumbler actuating member operable from the outside of the door for releasing the locking member, and means operable from the inside of the space closed by the door for moving said tumbler means to release the locking member.

10. A lock for vehicle doors comprising a latch

- bolt, an operating handle on the outside of the door and movable in opposite directions from normal position of rest, means mounted for rotation with the handle to retract the latch bolt
- 5 upon movement of the handle in one direction from normal position of rest, a locking member coacting with said latch bolt retracting means, means mounted for rotation with the handle to move said locking member into locking position
- 10 upon movement of the handle in opposite direction from normal position of rest, said locking member upon being moved to locking position engaging with said latch bolt retracting means to prevent movement of the handle in the direction corresponding to retraction of the latch bolt, tumbler means for holding the locking member in locking position, and means operable from the inside of the space closed by the door for moving said tumbler means to release the locking member.
- 15 11. A door lock comprising a latch bolt, a rotary member operatively connected to the latch bolt for retracting the latch bolt upon movement of said member in one direction, a locking member operatively connected to said rotary member to
- 20
- 25

be displaced upon a movement of the rotary member in opposite direction, said locking member upon being displaced effecting locking of the rotary member to prevent movement of the rotary member corresponding to retraction of the latch bolt, and means operable from the inside of the space closed by said door for effecting release of the locking member.

12. A door lock comprising a latch bolt, an operating handle on the outside of the door, 10 means operatively connected to the handle for retracting the latch bolt upon a movement of the handle, a locking member operatively connected to the handle to be displaced upon another movement of the handle, means mounted 15 for movement with the handle and engaging with said locking member upon the locking member being displaced whereby to prevent movement of the handle corresponding to retraction of the latch bolt, and an operating member distinct 20 from said handle and operable from the inside of the space closed by the door for displacing said locking member.

ETIENNE ARTHUR RENEVEY. 25
